UNITED STATES PATENT OFFICE.

WILLIAM EDWARD RAWLINGS, OF LYNNVILLE, ILLINOIS.

TENSION FOR CORN-PLANTER CHECK-WIRES.

SPECIFICATION forming part of Letters Patent No. 309,647, dated December 23, 1884.
Application filed September 16, 1884. (Model.)

To all whom it may concern:

Be it known that I, WILLIAM EDWARD RAWLINGS, of Lynnville, in the county of Morgan and State of Illinois, have invented 5 certain new and useful Improvements in Tensions for Corn-Planter Check-Wires, of which the following is a full, clear, and exact description.

Reference is to be had to the accompanying 10 drawings, forming part of this specification, in which similar letters of reference indicate corresponding parts in all the figures.

Figure 1 is a plan view of my improved tension for corn-planter check-wires. Fig. 2 is a 15 side elevation of the same. Fig. 3 is a sectional side elevation of the same. Fig. 4 is a sectional end elevation of the same, taken through the line *x x*, Fig. 3.

The object of this invention is to provide 20 means for giving a uniform tautness to corn-planter check wires or ropes each time the said ropes or wires are adjusted, so that the planting can be done in accurate check-row.

The invention consists in a tension for corn- 25 planter check-wires constructed with a stock having a longitudinal perforation provided with a spring, a sliding bar having a recess and an anchor-wire, a sliding bar having a forked hook to receive the check-wire, and teeth to 30 engage with a catch-plate provided with a lever and spring, and an operating-cord and its guide-pulley, whereby the check-wire can be put under a uniform tension. The tension is regulated by a plug screwed into the perforation of the stock for the tension-spring to rest 35 against.

A represents the stock of the tension, through which is formed a longitudinal perforation, B.

40 Within the perforation B is placed a spiral spring, C, the rear end of which rests against the forward end of a plug, D, screwed into the rear end of the perforation B, so that the tension of the said spring can be regulated by 45 turning the screw-plug D in or out.

Against the forward end of the spring C rests the inner end of a bar, E, the projecting outer end of which has a recess, F, formed in its upper side, to receive the catch-plate hereinafter described.

To the inner end of the bar E is attached the

end of a wire, G, which passes back through the spring C, through a longitudinal perforation in the adjusting screw-plug D, and has a loop in its projecting rear end to receive the 55 anchor-pin H. The head of the screw-plug D has radial holes formed in it to receive the anchor-pin H or other suitable implement for turning the said screw in and out.

In one side of the stock A is formed a dove-tailed groove, I, to receive the bar J, which has a hook, K, upon its forward end, which hook is slotted or forked to receive the check-wire L, the said slot being made of such a size that a knot, M, of the said check-wire 65 cannot pass through it.

In the upper edge of the bar J are formed 70 ratchet-teeth N, to receive the catch-plate O, placed at the forward end of the stock A, with its lower edge resting upon the upper edge of the bar E, the teeth N being so formed that the lower edge of the said catch-plate O will not engage with them until the said lower edge of the said catch-plate O drops into the recess F of the said bar E. The upper edge 75 of the catch-plate O is hinged to the forward end of a lever, P, which is fulcrumed to a support, Q, attached to the forward part of the upper side of the stock A, with its free end 80 projecting over the middle part of the said stock. The free end of the lever P is pressed upward, holding the catch-plate O down against the bar E by a U-shaped or other spring, R, interposed between the lever P and the stock A.

To the forward end of the bar J or the shank of the forked hook K is attached the end of the cord S, which passes along the lower side of the stock A, passes around a guide-pulley, T, pivoted in a short slot in a 90 projecting arm or flange at the rear end of the said stock A, passes along the upper side of the stock A, and through a keeper, U, attached to the said upper side or around a guide-pulley pivoted to the said upper side of 95 the stock A.

In practice a tension is designed to be applied to each end of the check-wire L. With this construction when the position of the check-wire L is to be changed, the tension is 100 taken to the new position, the said check-wire is drawn taut, and the anchor-pin H' is passed

through the loop of the wire G and forced into the ground, the bar J being kept from being drawn out of its socket by a stop-pin, V, attached to its rear part, and which strikes 5 against a keeper, W, attached to the side of the stock A. The keeper W is made in the form of a plate, and has a recess, X, in the upper edge to receive the edge of the catch-plate O, and which recess is made of such a 10 depth that its bottom will be on a level with the bottom of the recess F in the bar E, so that the said catch-plate when it drops into the recess F can engage with the teeth N of the bar J.

15 Upon the forward end of the stock A is formed a lug, Y, which projects upward at the outer side of the catch-plate O to keep the said catch-plate in place and prevent its lower part from swinging forward. The cord S is 20 then drawn upon, which forces the stock A forward and draws the bars J and E back, compressing the spring C, and putting the check-wire L under tension. When the desired tautness has been given to the wire L, the spring C 25 will be so much compressed that the catch-plate O will drop into the recess F of the bar E, and engage with a tooth, N, of the bar J, locking the various parts of the tension in place, so that by properly adjusting the 30 planter when starting in the field will be planted in accurate check-row.

Having thus described my invention, what I claim as new, and desire to secure by Letters Patent, is—

35 1. A tension for corn-planter check-wires, constructed substantially as herein shown and described, and consisting of the stock A, hav-

ing perforation B, provided with the spring C, the sliding bar E, having recess F and the anchor-wire G, the sliding bar J, having 40 forked hook K and teeth N, the catch-plate O and its lever and spring P R, and the cord S and its guide-pulley T, whereby the check-wire can be put under a uniform tension, as set forth.

2. In a tension for corn-planter check-wires, the combination, with the stock A and the spring C, of the screw-plug D, substantially as herein shown and described, whereby the said spring can be readily set to give any desired 50 tension to the check-wire, as set forth.

3. In a tension for corn-planter check-wires, the combination, with the stock A, the spring pressure bar E, having recess F, and the sliding bar J, having teeth N, of the catch-plate 55 O and its lever and spring P R, substantially as herein shown and described, whereby the said bars and stock will be locked together when the desired tension has been given to the check-wire, as set forth.

4. In a tension for corn-planter check-wires, the combination, with the stock A and the sliding bars J E, connected with the check-wire and the anchor-wire, of the cord S and guide-pulley T, substantially as herein shown 65 and described, whereby the said stock can be pushed forward and the said bars drawn back to give the desired tension to the check-wires, as set forth.

WM. EDWARD RAWLINGS.
